UNITED STATES PATENT OFFICE

LE ROY J. LEISHMAN, OF LOS ANGELES, CALIFORNIA, ASSIGNOR TO ELEC-TRU-TONE CORPORATION, OF LOS ANGELES, CALIFORNIA, A CORPORATION OF UTAH

TELEGRAPHOPHONE SYSTEM

Original application filed October 6, 1927, Serial No. 224,468. Divided and this application filed August 16, 1928. Serial No. 300,060.

This invention relates to electrical reproducers, and primarily to a simple and efficient apparatus for connecting an electrical pick-up for phonographs or telegraphophone sound box with the circuits of a radio receiving set so as to utilize the amplifier system thereof for reproducing phonograph selections without materially altering the circuits of the radio set or interfering with its 5 use as a receiver of radio signals at other times.

This application is a division of my application Serial Number 224,468, filed October 6, 1927.

15 In accordance with this invention provisions are made for connecting an electrical pick-up for phonographs or telegraphophone sound box either with the grid circuit or the plate circuit of the detector tube of the radio 20 set, preferably the grid circuit. In order conveniently to connect the electrical pick-up with the radio set without altering any of the connections of the set, an apertured disk is used which fits the prongs of the detector 25 tube between the tube and the contacts of the detector tube socket, making electrical connection with either the plate prong or the grid prong and also with the cathode prong when the usual AC tube is used or with one 30 of the filament prongs if the old A battery tube is used.

The invention will be described in detail in connection with the accompanying drawings and hereinafter claimed.

35 In the drawings:—

Figure 1 is a circuit diagram showing the manner of connecting a phonograph electrical pick-up with the detector grid circuit of a radio receiving set in accordance with 40 my invention.

Figure 2 is an elevation view of the lower portion of a radio detector tube with a disk in section to show contacts carried thereby for making connections with the pick-up in 45 accordance with this invention.

Figure 3 is a plan view of the contact disk.

Referring to the drawings, Figure 1 shows the detector and first stage of the audio amplifier only of any standard type of radio 50 receiving set employing a detector and one or

more stages of audio amplification. The detector tube is generally designated by the reference numeral 11 and the first audio transformer 12. The set is supplied with electrical energy at the proper potentials, 55 the sources shown being "A" and "B" batteries, and the detector circuit may be equipped with the usual grid leak resistance 13 and grid condenser 14.

In accordance with the present invention 60 an electrical pick-up for phonographs or telegraphophone sound box 15 is connected with the radio receiving set so as to utilize the amplifier system thereof for reproducing phonograph selections. Since the detector 65 tube will remain in its socket, and the circuit is not broken in any place, radio signals will come thru unless one of the radio frequency tubes is removed or, as will usually be the case, unless the set is detuned. While 70 I have illustrated the set using both "A" and "B" batteries, the tubes usually employed will be the more modern "AC" tubes.

The electrical pick-up 15 is provided with a connecting cable shown as wires 16 which 75 provide electrical connections for it with the grid circuit of the radio set by means of a plug 17 which is adapted to be inserted in a jack 18 the terminals of which are connected with the grid and the cathode terminal 80 of the detector tube 11. Between the wires 16 of the connecting cable a small case 19 is provided in which is a by-pass condenser 20 of approximately one microfarad and a variable modulating resistance 21. The case 85 19 is a standard unit providing a blocking condenser which is necessary in case the reproducer is connected to the plate terminals of the detector tube instead of to the grid terminal as preferred.

A connector for the electrical pick-up 90 preferably includes a very simple form of connection which consists of a disk 22 shown in Figures 2 and 3. This connector or disk has four or five holes for receiving the prongs of the detector tube 11, depending on whether battery or "AC" tubes are used. In the battery type, for example, one of the holes for the filament terminals such as the one receiving the prong 23 and either the plate of the 100

grid hole, according as to whether the circuit of the pick-up is to be made with the grid circuit or plate circuit of the detector of the radio set, are placed contacts 24 which engage the tube prongs, and wires 25 and 26 are connected to these contacts. The connector is very similar to my ordinary adapter, but provides simple and efficient means for making connection with the tube prongs with the tube in place in the tube socket without materially displacing the tube or taking up a great amount of space in the radio receiving set, as the disk 22 slips on the base of the detector tube and the leads are sufficiently small and flexible to fit easily between the tube and the old-fashioned socket should the latter be used.

In Figure 1, the preferred arrangement, the phonograph pick-up or telegraphophone is shown connected with the grid circuit of the detector tube, thus utilizing the amplifying effect of this tube as well as the audio amplifiers and by means of its connection therewith excluding the passage of radio frequency currents to the detector tube. However, as above referred to, the connections could as readily be made with the plate circuit of this tube by arranging the contacts 24 of the disk for such plate circuit connections in which event the blocking condenser 20 in the case 19 is necessary. The standard case 19 with the condenser and variable resistance are shown in the circuit of the pick-up for connection with the grid circuit (Figure 1); the condenser although not essential in this circuit is not objectionable and is retained in the circuit as a matter of convenience as a part of the standard equipment.

What I claim is:

- 40 1. In combination, a sound reproducer, a connector for making circuit connections with a radio tube consisting of contacts adapted to engage prongs of a radio tube while said tube is in its regular socket of a radio set and making all its normal electrical connections therewith, a supporting member for said contacts, and conductors connecting the reproducer and connector.
- 50 2. In combination, a jack, means for connecting said jack to a radio circuit, said means including a connector having contacts adapted to engage prongs of a radio tube while said tube is in its regular socket in a radio set and making all its normal electrical connections therein, a supporting member for said contacts and conductors connecting said contacts with the terminals of said jack.
- 60 3. The combination with a telegraphophone, of means for connecting the telegraphophone to a radio receiving set including conductor wires connected with the telegraphophone and a connector on the end thereof adapted to be positioned between the base of a tube and its mounting in the radio receiving set to connect the telegraphophone with one

of the circuits of the tube to utilize the amplifiers of the radio set, said connector while in operative position permitting all the tube prongs to engage the contacts of the regular tube mounting in the radio set in the usual way.

In testimony whereof I affix my signature.
LE ROY J. LEISHMAN.
